UNITED STATES PATENT OFFICE.

HENRY C. WEEDEN, OF BOSTON, MASSACHUSETTS. ASSIGNOR TO THE WEEDEN SANITARY MANUFACTURING COMPANY, OF RHODE ISLAND.

AUTOMATIC FLUSHING DEVICE.

SPECIFICATION forming part of Letters Patent No. 416,140, dated November 26, 1889.

Application filed May 25, 1889. Serial No. 312,070. (No model.)

To all whom it may concern:

Be it known that I, HENRY C. WEEDEN, of Boston, in the county of Suffolk and State of Massachusetts, a citizen of the United States, 5 have invented certain new and useful Improvements in Automatic Flushing Devices for Slop-Hoppers, Urinals, and Similar Structures, of which the following is a specification.

The object of my invention is to produce, in 10 connection with the ordinary flushing-tank or analogous structure for holding a supply of flushing-water and the bowl to be flushed, a combination of devices whereby the operation of flushing the bowl shall be automatic— 15 that is to say, shall occur whenever the bowl is used and in consequence of its use.

In the accompanying drawings I have represented an embodiment of my present improvement as applied to two forms of bowl to 20 be flushed, and I will now proceed to describe the structures therein represented.

In the drawings, A represents a flushing-tank of ordinary construction, and I have shown in connection with it the customary 25 supply-pipe and ball-cock.

B represents a flushing-pipe which extends from the tank to the bowl to be flushed. (Marked C.) The upper end of this flushing-pipe is to have a siphon-connection with the 30 water in the tank. I believe that the simplest and best way of providing this siphon-connection is, as represented in the drawings, by curving the flushing-pipe itself at its upper end to form a siphon, as shown.

35 D represents an outlet-pipe from the bowl. This outlet-pipe I join with the long leg of the flushing-siphon by means of an air-pipe E, and I place a suitable back-air cut-off in the flushing-pipe on the bowl side of the point 40 of entrance of the air-pipe. This back-air cut-off may be an ordinary trap-bend in the flushing-pipe, as shown in Figure 1 at F, or it may be a flap-valve, as shown at E' in Fig. 2. As the function of this back-air cut-off is to 45 prevent the passage of air from the bowl to the air-pipe E, it is obvious that either a water seal or a mechanical seal may be employed which will permit flushing-water to descend through the pipe to the bowl and yet will prevent 50 air from passing in the other direction.

In connection with the outlet-pipe, I form

upon the bowl side of the point of entrance of the air-pipe E an air cut-off d, to cut off the passage of air from the bowl through the outlet-pipe. This may be in the form of a water 55 trap, as shown in Fig. 1, or a float-valve. (Shown in Fig. 2.) I also provide a second air cut-off d' in connection with the outlet-pipe and at a point upon the sewer side of the point of juncture with it of the air-pipe. This 60 I preferably make in the form of an S-bend, thereby forming in connection with the outlet-pipe a siphon, as in Fig. 1. The air cut-off may, however, be conveniently formed by simply dipping the end of the pipe in a body of 65 water, as shown in Fig. 2. The outlet-pipe at its lower end may connect with any suitable pipe leading to the sewer or other waste-receptacle.

The operation of the device is as follows: 70 When the apparatus is at rest, the various traps or seals stand closed, as shown. If, now, liquid be poured into the bowl to be flushed, it passes down the outlet-pipe, and passing the air cut-off d therein flows past the lower 75 extremity of the air-pipe and continues to flow downwardly and outwardly through the outlet-pipe and through the second seal thereof. Inasmuch as the air-seal in the outlet-pipe next the bowl prevents the passage of 80 air from the bowl, it is obvious that when the water introduced into the outlet-pipe and flowing through it, as described, drives the air therein before it a more or less complete vacuum will thereby be caused in the outlet-pipe, 85 and the air from the air-pipe and from the long leg of the flushing-siphon expanding to fill the vacuum so created will be rarefied sufficiently to start the siphon automatically, the back-air cut-off in the siphon flushing- 90 pipe preventing the inrush of air from the bowl. Of the water thus descending the main portion will pass through the flushing-pipe and so thoroughly flush the bowl. After the flushing is terminated by reason of the siphon in the flushing-tank breaking itself and the flushing-water has run off the various traps or seals will be left closed in their normal condition. When the outlet-pipe is so formed, 95 as above explained, to contain a siphon upon 100 the sewer side of the point of entrance of the air-pipe E, the short leg of which siphon is

nearest to the air-pipe, it is evident that the action of this siphon itself, when started by the flow of water coming from the bowl, will aid in withdrawing the water from that portion of the outlet-pipe into which the air-pipe leads, and so will be efficient in producing the vacuum therein, upon which the operation of the structure depends.

It is obvious from what has already been said that the outlet-pipe should be so constructed and of such a capacity relatively to the bowl that the amount of liquid which will be introduced into it in use when passing down the outlet-pipe may fill it full bore, so as thoroughly and completely to drive out the air therefrom. This consideration will therefore determine to a certain extent the area of the outlet-pipe. With certain classes of bowls—as, for example, those used in slop-hoppers—the amount of liquid poured in will be large enough to fully fill an outlet of a capacity equal to that of the flushing-pipe by which the bowl is flushed, and under these circumstances the outlet-pipe will obviously be all that is required to carry off the flushing-water. In the case of urinals, on the other hand, as the amount of liquid introduced into the bowl may be relatively small, it may be under certain circumstances necessary to employ an outlet-pipe of a capacity less than that of the flushing-pipe which it is desired to use. Should this be the case an overflow or supplemental outlet E may be provided, as shown in Fig. 2, and the outlet and overflow may of course be united, as shown, to avoid the expense of running two separate pipes to the drain.

I claim—

1. In an automatic flushing device, the combination, with the bowl to be flushed, of a supply-tank, a siphon flushing-pipe extending from the tank to the bowl, an outlet-pipe from the bowl, an air-pipe extending from the long leg of the siphon flushing-pipe to the outlet-pipe, a back-air cut-off in the long leg of the flushing-pipe on the bowl side of the point of entrance of the air-pipe, and two air-seals in the outlet-pipe located, respectively, on the bowl side and on the sewer side of the point of junction therewith of the air-pipe, all substantially as set forth.

2. In an automatic flushing device, the combination, with the bowl to be flushed, of a supply-tank, a siphon flushing-pipe extending from the tank to the bowl, an outlet-pipe from the bowl, an air-pipe extending from the long leg of the siphon flushing-pipe to the outlet-pipe, a back-air cut-off in the long leg of the flushing-pipe on the bowl side of the point of entrance of the air-pipe, and an air-seal in the outlet-pipe located on the bowl side of the point of juncture therewith of the air-pipe, and a second air-seal therein on the sewer side of said point or juncture, this latter air-seal consisting of a siphon, substantially as described.

In testimony whereof I have hereunto subscribed my name this 21st day of May, A. D. 1889.

HENRY C. WEEDEN.
